IGNITION APPARATUS

Edward B. Nowosielski, Bloomfield, N. J., assignor
to Eclipse Aviation Corporation, East Orange,
N. J., a corporation of New Jersey

Application November 5, 1935, Serial No. 48,415

3 Claims. (Cl. 123—169)

The present invention relates to ignition apparatus for internal combustion engines, and more particularly to spark plugs.

One of the objects of the present invention is to provide novel means for thermally and electrically shielding spark plugs in order to avoid injury thereto by excessive heat accumulation at vulnerable points, and to prevent electrical interference with sensitive electrical equipment in the vicinity, such as radio receiving apparatus.

Another object is to provide a novel spark plug shield which is light in weight, simple in construction and inexpensive to manufacture.

15 A further object is to provide a metallic shield for a spark plug which may be readily and easily assembled or disassembled, and which is adapted for use with any of the usual types of spark plugs.

20 Still another object is to provide a spark plug shield in which the proper clearance between its metallic parts and the high tension terminal of the spark plug is maintained by the provision of novel insulating and heat resisting supporting means which also provides a support for the ignition cable which is connected to the high tension terminal.

25 A still further object is to provide a novel shield for spark plugs which is both mechanically rugged and electrically efficient for shielding purposes, and yet requires only a minimum of shielding and insulating material.

30 These and other objects of the invention will become apparent from inspection of the following specification when read with reference to the accompanying drawing wherein is illustrated the preferred embodiment of the invention. It is to be expressly understood, however, that the drawing is for the purpose of illustration only, and is not designed as a definition of the limits of the invention, reference being had to the appended claims for this purpose.

In the drawing:

Fig. 1 is a longitudinal sectional view of the shield in its preferred form shown in its pre-relation to the spark plug when completely installed and secured in place; and

Fig. 2 is an exploded perspective view of the adjustable means for holding the shield in place.

50 In the form shown, a cup-shaped metallic shielding member 4 constitutes the lower part of the shield, and surrounds and extends substantially the length of a spark plug 5 which is to be shielded. This spark plug may be of any of the usual types and is provided with a high tension

terminal 6 to which is connected the positive electrode 7. A body portion 8 receives the negative electrode 10, and is adapted for threaded engagement with an orifice in the cylinder wall of an internal combustion engine. Shielding member 4 is provided with an inturned annular lip or flange 11 at its lower end which is adapted to fit under flange 9 of the spark plug and to be securely held between said flange and the outer surface of the engine cylinder wall when the spark plug is 10 threaded therein. Shielding member 4 may also be provided with a plurality of louvres or apertured niches (not shown) circumferentially spaced around its lower portion to ventilate and cool the lower portion of spark plug 5, and also 15 to allow the drainage of any moisture which might form on the shield.

An upper shielding member or cap 13 has an annular base 14 adapted to rest on rim 16 of the member 4, and a threaded extension 15 to 20 receive the end of a metallic sheath (not shown) enclosing the ignition cable. The top surface of cap 13 is flattened to receive the base of an adjusting cap 51, the lower portion of which is knurled as indicated in Fig. 2 at 52, and the 25 upper portion of which is internally threaded as indicated at 53, and radially grooved as indicated at 54 in Fig. 2, the purpose of the threads being to receive the corresponding threaded screw 56, and the purpose of the radial grooves being 30 to receive the oppositely extending arms of the locking pin 57, the said arms being also received in the axially extending slot 58 in the screw 56. As shown, the screw 56 is counterbored to receive 35 a coiled compression spring 59 and a pressure plate or disc 61 against which one end of the spring bears to exert pressure upon the central portion 62 of a wire bail or clamp 63 passing through the slot 58 of the pin 56 and extending downwardly to terminate in inwardly turned ends 40 64 and 65 pivotally received in openings formed in the downwardly extending skirt 66 of the rim 16 of the lower shield 4. The type of wire bail shown at 3 has, of course, been used heretofore, but in former installations the resiliency of the 45 bail has been relied upon as practically the sole means of locking the cap in position. In practice it has been found that this is not sufficient, particularly after repeated removals and re-applications of the bail from which manipulation thereof tends to interfere with its initial tension, and thereby reduces the effectiveness of the grip. In the construction above described, I provide means for compensating for such variations in the form of the adjusting elements indicated 55

at 52. With these adjusting elements the operator may raise the pin 57 out of the grooves 54 with which it registers, and then turn the adjusting cap 58 on the threads of the screw 56 until the slack between the screw and portion 62 of the bail has been eliminated, whereupon the bar 57 is allowed to return to engagement with the registering set of grooves 54, thereby holding the re-tensioned bail securely and insuring its continued effectiveness as a retaining means for cap 13.

The present invention also includes a novel form of insulation to be placed between the high tension terminal and the metallic shield, to per-
15 form not only its electrical function in an effi-
cient manner, but also to act as a barrier block-
ing heat flow in the direction of the terminal
connection with the ignition cable. In the form
shown, the combined insulating and heat resist-
20 ing means referred to comprise a lower insulating
member 17 of suitable heat resisting material,
such as asbestos, and an upper insulating mem-
ber 18 preferably molded within cap 13, and pro-
vided with a longitudinally elongated portion or
25 boss 21 which is coaxial with part 15 of the cap,
and forms an insulated entrance for the ignition
cable which is adapted for connection to terminal
6 by any suitable means such as the screw shown
at 23. Preferably this screw is disposed with its
30 axis in alignment with the axis of the plug 5, and
with its upper end pointed to pierce both the in-
sulation and the metal stranded wire which com-
pose the current conducting ignition cable, the
head 24 of the screw being in engagement with a
35 conducting washer 26 fitting within the innermost
portion of the recess 27 in the cap 18, the said
recess being formed by the downwardly extending
skirt 28 of the cap. A coil spring 29 surrounds
40 and contacts ring 26 and has its lower end bent
downwardly through the central opening 31 in
the member 17 to be received within the terminal
6 of the plug and thereby complete the electrical
circuit to the electrode points 7 and 10.

By reason of the transversely extending por-
45 tion 43 of the member 17 the flow of heat toward
the conducting parts adjacent the cable is effec-
tively blocked, and the flow is thus deflected from
the metallic elements 40 and 4 to the outer sur-
face of the cap 13 and the atmosphere. To sup-
50 plement member 17 in resisting the current con-
ducting elements, I provide washers 36 and 37,
which are also of heat resisting material such as

asbestos, the said washers being engageable with
the upper and lower surfaces of the rim 39 on the
metallic cup 40 within which the member 17 is
positioned and retained (as by being molded
therein) the washer 37 serving as a support for 5
the cup 40 and the member 17 and being in turn
supported by the rim 16 of the shielding element
4. Preferably, the base and sides of the cup 40
are apertured as indicated at 70 and 71 respec-
tively, and opposite the apertures 71 the insulator 10
17 is made of reduced diameter to provide an
annular chamber facilitating free radiation of
heat from the insulator and into the outer an-
nular chamber by way of apertures 71.

Various changes, which will now appear to 15
those skilled in the art, may be made in the
form, details of construction and arrangement of
the parts without departing from the spirit of
the invention, and reference is therefore to be
had to the appended claims for a definition of 20
the limits of the invention.

What is claimed is:

1. A shield for a spark plug and cable con-
ductor comprising a lower shielding member sur-
rounding the plug, an upper shielding member 25
surrounding and receiving the cable conductor, a
conducting member connecting said cable con-
ductor and plug, a heat resisting insulator sur-
rounding said conducting member and the upper
part of the plug, a metallic cup enclosing said in-
sulator, said cup having a rim contacting said
upper shielding member, and a second member of
heat resisting material interposed between said
cup and lower shielding member.

2. The combination, with a spark plug shield 35
having upper and lower sections and a wire bail
uniting said sections, of a bail receiving cap on
said upper section, and means for taking up play
between the bail and the bail receiving cap, said
last-named means including a pin engageable 40
with said cap to lock the latter in a predeter-
mined position in relation to said bail.

3. A shield for a spark plug and cable com-
prising a lower shielding member surrounding 45
the plug, an upper shielding member surrounding
and receiving the cable, a conducting member
connecting said cable and plug, a heat resisting
insulator surrounding said conductor and the up-
per part of the plug, a metallic cup enclosing said
insulator, and a heat radiating chamber between 50
the insulator and cup.

EDWARD B. NOWOSIELSKI.
